UNITED STATES PATENT OFFICE.

WILLIAM A. FULD, OF BALTIMORE, MARYLAND.

TOY.

Application filed July 31, 1926. Serial No. 126,326.

The invention relates to toys and has as an object the provision of a toy animal or bird which when drawn along a supporting surface will have a movement of the limbs and

5 a lifelike motion of the body of the toy.

A further object of the invention is the provision of a supporting wheel for such a toy designed to give the lifelike motion referred to.

10 An illustrative embodiment of the invention is shown in the accompanying drawings wherein:

Figure 1 is a side elevation;

Figure 2 is a bottom plan view;

15 Figure 3 is a vertical section on line 3—3 of Figure 1 on an enlarged scale;

Figure 4 is a detail vertical section on line 4—4 of Figure 3.

As shown the device has a body 10 which 20 for the purpose of illustration is made in the outline of a duck and a flexible member 11 is shown attached to the body as by means of a staple 12 for traction.

To cause a waddle of the body by elevating first one side and then the other thereof, there is shown a wheel 13 housed in a recess 25 14 in the lower side of the body 10 pivoted upon an axis 15.

As shown the wheel comprises two circular discs 16, 17, eccentrically mounted upon the axis 15, the eccentricities of the two discs being diametrically related to each other. The discs 16, 17, are preferably rigidly secured together. When the body 10 is drawn 30 along the surface 18, the projecting portions of the two discs will alternately contact with the surface slightly lifting the body first in one lateral direction and then in the other whereby to cause the lifelike waddle above 35 referred to.

To add a lifelike appearance to the toy, legs 19, 20 are loosely pivoted upon the two sides of the body as by means of screws 21, 22, washers 23, 24, being desirably provided 40 to assist the freedom of motion of the legs. The lower ends of the legs 19, 20, are formed to simulate feet at 25, 26, which feet are mounted to clear the supporting surface or at most to contact therewith only when the 45 body is tilted to that side of the toy and such contact is not depended upon for motion of the feet.

To cause a stepping motion of the feet and legs, there is provided upon each side of 50 wheel 13 a cam shown at 27, 28, a detail of which is shown in Figure 4, and a pin 29, 30,

is rigidly carried by each of the feet and the pins project through slots 31, 32, in the side walls of the recess 14 into the paths of cams 27, 28.

55 The cams 27, 28, are rigidly secured to the wheel 13. It will therefore be seen upon inspection of Figure 4 that the pins 29, 30 will be forced rearwardly thereby oscillating the feet 25, 26, and the corresponding legs 60 rearwardly as the body is tilted until the corresponding pin escapes from the nose of the cam when the operated leg will return to its normal position by gravity.

65 By providing the wheel 13 formed of two circular discs, the same may be very readily manufactured by the expedient of producing a large number of like discs and assembling two of the same in the described relation for each wheel. The operation of the device 70 will be clear from the above description.

75 Minor changes may be made in the physical embodiment of the invention within the scope of the appended claims without departing from the spirit thereof.

I claim:

1. A toy comprising, in combination, a body having a recess therein, a wheel journaled to rotate on an axis in said recess and projecting therefrom to contact with a supporting surface, said wheel comprising like disks rigidly secured in contact with each other and eccentrically on said axis, the eccentricity of said disks being out of register 85 whereby to cause oscillation of said body during progression thereof.

2. A toy comprising, in combination, a body having a recess therein, a wheel journaled to rotate on an axis in said recess and projecting therefrom to contact with a supporting surface, said wheel comprising like disks rigidly secured in contact with each other and eccentrically on said axis, the eccentricity of said disks being diametrically opposite whereby to cause oscillation of said 95 body during progression thereof.

3. A figure toy comprising, in combination, a body simulating an animate figure, a supporting wheel journaled thereon, a cam surface carried by said wheel, a member 100 freely pivoted on said body, having a part projecting into the path of movement of said cam and adapted to be moved rearwardly by said cam whereby to simulate walking movement of said member.

WILLIAM A. FULD.
